SOLID FUEL COMBUSTION APPARATUS

Ernest Lambert Tinley, Lower Penn, near Wolverhampton, and Frederick Arthur Driver, Penn Wolverhampton, England, assignors to Joshua Bigwood and Son Limited, Wolverhampton, England, a British company

Application October 4, 1951, Serial No. 249,673

7 Claims. (Cl. 110—29)

1

This invention relates to solid fuel combustion apparatus and refers to that type of combustion apparatus in which the fuel is fed to a combustion chamber, usually from above one end, and forms a bank of fuel extending across the chamber, the fuel being ignited at the opposite end at a position disposed at the end of the bank where the bank of fuel provides a surface which is usually inclined at the angle of repose, and where-in one or more jets of air are directed onto this surface where combustion is taking place, the combustion chamber having an outlet for the products of combustion which may pass to a boiler or other structure used for water heating or steam generating or crop drying, or other useful purpose.

The temperature at which the apparatus operates may be controlled by a thermostat which controls an electric motor supplying the air to the air jet so as to regulate the supply of air to the jet or the thermostat may control a valve in the air duct.

It is a characteristic of this type of apparatus that the interior of the fuel bed remains at a high temperature for a considerable time after the air has been shut off, and this is of importance when the operation of the apparatus is intermittent, because the fire bed can be fully alight in a short time when the air supply is restarted.

However, it has been found in practice to be desirable to maintain combustion at a slow rate during periods when the air supply is shut off (i. e. when the apparatus is not operating on load), so as to ensure that sufficient fire exists in the combustion chamber to ignite the fuel bed fully when the air supply is restarted and the object of the present invention is to provide means for achieving this.

According to the present invention we provide an auxiliary air supply for promoting a slow rate of combustion in the combustion chamber during periods when the main air supply to the air jet is shut off and means for controlling the auxiliary supply so that auxiliary air is only admitted when the main air supply is shut off.

Preferably automatic means are provided for controlling the auxiliary air supply and such means may be operated from the main air supply so that when the main air supply is stopped, the auxiliary supply is started and continues until the main supply is again started.

The auxiliary air supply may be controlled by a valve which is subject to the pressure of the air in the main supply so that this valve is kept closed to shut off the auxiliary air until the main supply

2

is stopped and the reduction in pressure allows the valve to open and admit auxiliary air to the combustion space.

The combustion chamber of the apparatus is preferably provided with a grate at the bottom of the chamber and the delivery end of the auxiliary supply line disposed so as to be in communication with the space below this grate.

The invention is illustrated in the accompanying drawings, wherein—

Figure 1 is a section in side elevation through combustion apparatus of the present invention.

Figure 2 is a section on the line 2—2 in Figure 1.

Figure 3 is a detail view of one form of automatic control valve for the auxiliary air supply.

Figure 4 is a section on the line 4—4 in Figure 3.

Figures 5 and 6 show two alternative forms of auxiliary air control valve.

In the construction shown in the accompanying drawings the combustion apparatus is constructed with a combustion chamber 10 of box-like form which is fed with fuel from a hopper 11. An inclined sealing plate 12 is provided at one end of the chamber and at one or both sides openings 25 are provided for the removal of clinker in the manner described.

The side walls 12, top 13 and front wall 14 are of double walled construction and water is circulated through the space between the double walls 30 through pipes 15 from a pump 16. The hot gases from the combustion chamber pass out through an opening 17.

For the purpose of the present invention the bottom of the combustion chamber is provided 35 with a grate which defines the floor of the combustion chamber and comprises an upper flat part 18 supported by suitable legs 19 so that it is spaced away from the base 20 of the apparatus and there is provided below the grate a clear space 21. The grate itself may be of the usual form, of grid formation so that fine ash and dust can pass through into the space below from which it may be periodically removed.

The main air supply is provided by a fan 22 45 driven by an electric motor 23 and this fan is disposed in one end of the apparatus behind the inclined sealing plate 12 and the main air supply duct 24 from the fan passes around one side of the apparatus to the air jet 25 which is disposed 50 at the forward end at the top of the combustion chamber. A tank 26, which supplies paraffin through a pipe 27, is provided to facilitate ignition of the fuel.

The duct 24 as shown in Figure 4 is provided 55 with a damper 28 which may be adjusted by

means of a knob 29 from outside the outer casing.

The auxiliary air supply of the present invention is provided by means of a pipe 30 which has one end 31 in communication with the space 21 below the grate in the combustion chamber and this pipe is conveniently disposed in a vertical position at one side of the combustion chamber and is housed between the outer casing 32 of the apparatus and the outer wall of the double-walled construction of the combustion chamber. The lower end of the pipe communicates with the space below the grate and at its other end the pipe is connected to a valve generally indicated at 33 in Figure 1, which automatically controls the admission of auxiliary air to the combustion chamber.

In the form of the valve shown in Figures 3 and 4, the pipe 30 is connected to a valve box 34, housing a hinged vane 35 which closes apertures 36 in the end of the valve box. This end is inclined so that when hanging freely the vane 35 permits air to enter from the atmosphere and pass through pipe 30 to the bottom of the combustion chamber.

The duct 24 opens into the valve box 34 through apertures 37 so that when the main air supply is on the vane 35 is held closed by the pressure of air on its rear face.

In Figure 6 is shown an alternative form of valve which comprises a cylindrical casing 38 which is disposed in operation with its axis in a vertical plane and at each end the casing has end plates 39 and 50 with projecting flanges through which pass securing bolts 40 which secure the two ends of the casing to the central cylindrical part.

At its lower end the end plate 50 of the casing is connected by means of a pipe 41 to the main air duct 24 leading from the main supply fan and at the other end the end plate 39 has a centrally disposed aperture 42 to which is connected the end of the auxiliary air supply pipe 30.

The movable valve member within the casing comprises a piston which is formed with an outer cylindrical skirt 43 which works upon the inner face of the casing 38 and a centrally disposed tubular portion 44 connected to the outer skirt 43 and of greater axial length than the skirt extending forwardly towards the upper end of the casing. The forward end 45 of this part 44 of the piston is shaped to engage a valve seat 46 on the central aperture 42 in the end plate 39.

When the piston is in the position in which its forward end 45 engages this valve seat 46 there is a substantial distance between the forward end of the piston skirt and the upper end plate and within this distance the outer cylindrical casing is provided with a number of ports 47 which open to the atmosphere.

When the main air supply is on, the pressure of air at the back of the piston keeps its upper end 45 in engagement with the valve seat 46 so that no air can pass through the casing ports 47 into the auxiliary line 30 but when the main air pressure is reduced, that is when the fan is stopped, the valve piston descends within the casing thus allowing air from atmosphere to pass through the casing ports into the auxiliary line.

To regulate the amount of auxiliary air which can enter, the lower end plate 50 is provided with an adjusting screw 48 which passes through the end plate vertically and has its upper end disposed within the tubular part 44 of the piston. By screwing the adjusting screw inwardly or outwardly of the end plate 50 the distance travelled

by the piston when it descends can be decreased or increased respectively so that the opening between the forward end 45 of the piston and the valve seating 46 can be adjusted to regulate the amount of air from atmosphere passing into the auxiliary line 30.

In a further form shown in Figure 5 the valve casing may be arranged as before with connections 41 to the main air supply and auxiliary line 30 as in the previous form but instead of a piston a flap or vane 49 is provided hinged about a horizontal axis to the upper end plate 51 and arranged so that when the main air supply is on the pressure of air in the casing maintains the flap closed against the opening 42 to the auxiliary line. The upper end plate 51 is also provided with ports 50 to atmosphere which are also closed by the flap 49 when it closes the auxiliary line so that when the flap descends under gravity due to the stopping of the main fan these atmospheric ports are uncovered to allow air to pass into the casing and through the opening in the end plate into the auxiliary line 30. An adjusting screw 48 may be provided in the lower end plate 52 as before with its upper end adapted to be engaged by the flap when it descends so that the opening provided between the flap and the end plate 51 can be adjusted to regulate the admission of air from the atmosphere.

30 By this means a regulated quantity of air can be supplied to the combustion chamber so as to maintain combustion at a slow rate during the time that the main air supply is shut off.

What we claim then is:

35 1. In solid fuel combustion apparatus comprising a combustion chamber, means for continuously feeding fuel thereto from above at one end so as to form a bank of fuel extending across the chamber to the opposite end and providing an inclined surface, means for directing air under pressure from above on to said inclined surface, and a main air supply for supplying air under pressure to said air-directing means; means for promoting a slow rate of combustion when the main air supply is shut off comprising an auxiliary air supply and automatic means for controlling said auxiliary air supply so that auxiliary air is only admitted when the main air supply is shut off, said automatic means being operatively connected with the main air supply so as to be actuated by the stopping and starting of the main air supply.

2. In solid fuel combustion apparatus comprising a combustion chamber, means for continuously feeding fuel thereto from above at one end so as to form a bank of fuel extending across the chamber to the opposite end and providing an inclined surface, means for directing air under pressure from above on to said inclined surface, and a main air supply for supplying air under pressure to said air-directing means, means for promoting a slow rate of combustion when the main air supply is shut off comprising an auxiliary air supply and a valve controlling said auxiliary air supply, said valve being subject to pressure of the air in the main supply so as to keep the valve closed until the main supply is shut off.

3. In solid fuel combustion apparatus comprising a combustion chamber, means for continuously feeding fuel thereto so as to form a bank of fuel extending across the chamber and providing an inclined surface, means for directing air under pressure from above on to said inclined surface, and a main air supply for sup-

plying air under pressure to said air-directing means, means for promoting a slow rate of combustion when the main air supply is shut off comprising an auxiliary air supply, a valve controlling said auxiliary air supply, said valve being subject to pressure of the air in the main supply so as to keep the valve closed until the main supply is shut off and said valve comprising a valve casing having a movable valve member housed therein said valve member being subject to the pressure of air in the main supply so as to keep it in the closed position against the action of gravity until the main air supply is shut off.

4. In solid fuel combustion apparatus comprising a combustion chamber, means for continuously feeding fuel thereto so as to form a bank of fuel extending across the chamber and providing an inclined surface, means for directing air under pressure from above on to said inclined surface, and a main air supply duct for supplying air under pressure to said air-directing means, means for promoting a slow rate of combustion when the main air supply is shut off comprising an auxiliary air supply, a valve controlling said auxiliary air supply said valve being subject to pressure of the air in the main supply so as to keep the valve closed until the main supply is shut off, said valve comprising a valve casing mounted on the main air supply duct, one end of said casing being in communication with the inside of the main air duct, the other end of said casing having ports therein open to the atmosphere and an opening connected to the auxiliary supply, and a vane hingedly mounted on this end of the casing, said vane being adapted to cover said ports and said opening in the closed position and being held in the closed position by the pressure of air in the main supply duct.

5. In solid fuel combustion apparatus comprising a combustion chamber, means for continuously feeding fuel thereto so as to form a bank of fuel extending across the chamber and providing an inclined surface, means for directing air under pressure from above on to said inclined surface, and a main air supply for supplying air under pressure to said air-directing means; means for promoting a slow rate of combustion when the main air supply is shut off comprising an auxiliary air supply, a valve controlling said auxiliary air supply, said valve being subject to pressure of the air in the main supply so as to keep the valve closed until the main supply is shut off, said valve comprising a valve casing arranged with its axis vertical, having an opening in the top end connected to the auxiliary air supply and an opening in the bottom end connected to the main air supply, a piston-shape valve member working in said casing and the upper part of said casing having ports therein open to the atmosphere, said valve member being adapted to cover said ports in the closed position and being held there by the pressure of air in the main air supply.

6. In solid fuel combustion apparatus compris-

ing a combustion chamber, means for continuously feeding fuel thereto so as to form a bank of fuel extending across the chamber and providing an inclined surface, means for directing air under pressure from above on to said inclined surface, and a main air supply for supplying air under pressure to said air-directing means, means for promoting a slow rate of combustion when the main air supply is shut off comprising an auxiliary air supply, a valve controlling said auxiliary air supply said valve being subject to pressure of the air in the main supply so as to keep the valve closed until the main supply is shut off, said valve comprising a valve casing arranged with its axis vertical, having an opening in the top end and an opening in the bottom end, pipes connecting said openings to the auxiliary and main air supplies respectively, a hinged vane pivoted on a horizontal axis to said top end of the casing, said top end of the casing having ports therein open to atmosphere and said vane being adapted to cover said ports and the opening in the top of the casing when in the closed position and being held closed by the pressure of air in the main supply.

7. In solid fuel combustion apparatus comprising a combustion chamber, means for continuously feeding fuel thereto so as to form a bank of fuel extending across the chamber and providing an inclined surface, means for directing air under pressure from above on to said inclined surface, and a main air supply for supplying air under pressure to said air-directing means, means for promoting a slow rate of combustion when the main air supply is shut off comprising an auxiliary air supply, a grate disposed in the bottom of said combustion chamber, said auxiliary air supply including a pipe line for air having its delivery end disposed below said grate, and automatic means for controlling said auxiliary air supply so that auxiliary air is only admitted when the main air supply is shut off said automatic means being operatively connected with the main air supply so as to be actuated by the stopping and starting of the main supply.

ERNEST LAMBERT TINLEY.
